UNITED STATES PATENT OFFICE.

JOHN W. CHILDS, OF KANSAS CITY, MISSOURI.

IMPROVEMENT IN SCHOOL-DESKS.

Specification forming part of Letters Patent No. 139,543, dated June 3, 1873; application filed April 28, 1873.

To all whom it may concern:

Be it known that I, JOHN WALLACE CHILDS, of Kansas City, in the county of Jackson and State of Missouri, have invented a new and useful Improvement in School-Desks; and I do hereby declare the following to be a full, clear, and exact description of the same, reference being had to the accompanying drawing forming a part of this specification.

The invention relates to a peculiar side brace applied to desks or other analogous articles, as hereinafter described and pointed out in the claim.

I will now describe and illustrate my invention as applied to a school-desk.

Figure 1 is a side elevation, and Fig. 2 is a vertical section.

In the drawing, A A represent the metallic sides, spaced and held apart by intermediate pieces, and connected with a back, B. C is the lid, and D the seat. None of these form any part of my invention. E is a side brace applied to top C and made of metal, having the slots e e^1 e^2 e^3 , the former being preferably at right angles to the plane of top, in order to allow it to be lifted, while the other is arc-

shaped at e^1 e^2 , and connected together by the vertical part e^3 . a is the pintle on which the brace turns, and a^1 the stop by which it is held in the oblique position required for the use of the scholar. At one end of the arc-slot e^2 is formed a shoulder, e^4 , that is held by the gravity of desk-top C against the stop a^1 . Thus held, the top C is ready to receive the books of the scholar, and when it is desired to turn down the desk-top it is lifted and the stop carried out of one arc-slot down through vertical slot into the other. This allows the lid to be turned on the pintle a and folded against the back.

Having thus described my invention, what I claim as new, and desire to secure by Letters Patent, is—

The side brace E of the desk-top, having the slot e and curved slot e^1 e^2 e^3 , constructed and combined with the pintle a and stop a^1 , as and for the purpose described.

JOHN W. CHILDS.
